UNITED STATES PATENT OFFICE.

AUGUST SUNDH, OF HASTINGS-UPON-HUDSON, NEW YORK.

GATE-HINGE.

1,156,943.

Specification of Letters Patent.

Patented Oct. 19, 1915.

Application filed February 10, 1915. Serial No. 7,230.

To all whom it may concern:

Be it known that I, AUGUST SUNDH, a citizen of the United States, residing in Hastings-upon-Hudson, in the county of 5 Westchester and State of New York, have invented a new and useful Improvement in Gate-Hinges, of which the following is a specification.

My invention relates to an improvement 10 in gate hinges of the self-closing type, known in the art as gravity hinges.

This arrangement has for its objects the provision of a hinge which will be well lubricated at all times, thoroughly protected 15 from the elements, easy in operation, easy of assembly, and one which will be self closing.

With the improvement I have shown in my device, the same enables me to suspend the load from the hinge member which is fastened to the gate post instead of the load 20 resting on this member. This does away with the necessity of having overhanging supports from the gate post to the gate to take care of sagging of the gate, and it also 25 insures the load of the gate hanging in a straight line through the hinge.

These and other advantages are fully pointed out in the following description and the annexed claims.

Referring to the accompanying drawings, illustrating my invention, Figure 1, is an elevational view partly in section, of my device applied to a gate; Fig. 2 is a sectional elevational view taken at right angles to Fig. 1; Fig. 3 is a plan view taken on the line 2—2 of Fig. 2; Fig. 4 is an elevational view illustrating my device in place on a gate; Fig. 5 is a view similar to Fig. 4, but showing the hinge applied to the opposite 40 end of the gate from that shown in Fig. 4; and Fig. 6 is a cross section of the hinge shown in Fig. 5.

Referring to the drawings in detail, my device comprises two telescopic cylindrical parts, referring now to Figs. 1, 2 and 4, the part designated as 2 being fastened to the gate, and the part, 1, being fastened to the gatepost. The part 2 has an extension, 3, pivoted to a clamping member 4, by which 45 the hinge is secured to the gate. The manner in which I fasten the hinge to the gate is the best in practice, as I have found by experience, permitting very quick application of the hinge. The part 1 has an extension, 5, by means of which the hinge member 1 is secured to the gate post. A boss 6,

is formed on the upper end of the member 1. Extending up through the upper member 1 and into the boss 6 where it is held fixed by reason of being forced into the boss, is a 60 spindle 7. A cylindrical cup 8 of slightly less diameter than the part 2 is formed on the inside of the part 1. This cup 8 is rather peculiar in shape and for that reason rather difficult to describe clearly, but the drawings 65 show the shape perfectly. The bottom of the cup forms a cam 9 which surrounds the spindle 7, an opening being provided in the bottom of the cup to permit of the entry of the spindle 7 as well as a portion of the 70 other member 2, which will be described later.

The cup 2 has formed on its inside and concentric with its walls an upwardly extending cylinder 10 the bore of which is 75 slightly larger than the diameter of the spindle 7. With the parts in central position, this cylinder is long enough to extend up through the bottom of the part 8 a short distance, in fact it is the same length as the 80 inside of the cup 2. Near the top of the cylinder and formed on it is a shoulder 11. This shoulder, which extends only partly around the periphery of the part 10, carries a round headed stud or pin 12, adapted to 85 engage the bottom of the cup 8, or to be more exact, it rests in a recess 13, formed in the cam 9. While the cam, 9, may generally speaking, be referred to as one cam, it is more properly two cams, meeting at 90 their lower ends, a recess, 14, being provided at this point for the end of the pin, 12, to rest in when the gate is in central position. This recess tends to a certain extent to overcome the tendency of the gate to see-saw 95 by central position when closing. At the upper end of the cam member, 9, a slot, 15, is provided which slot is cut right through the cam member. This slot is provided to enable the hinge to be assembled. It should 100 be understood that the parts are so positioned, that when the gate is closed, the pin, 12, rests in the recess, 14, and when the gate is all the way open the pin has traveled up the cam member near to the slot, 15. The 105 cup 2 is filled with oil when the hinge is in use. The relative lengths of the parts is such that the cup 1 always telescopes the cup 2, and the spindle, 7, does not ride out of the extension 10. This applies, of course, 110 to the hinge in operation.

Referring now to Figs. 5 and 6, these

figures, as already stated, are practically duplicates of the other figures, except that in this instance the hinge is applied to the lower part of the gate. Two telescoping 5 parts, 1' and 2', are provided, as in the other type of hinge already described, the part 2' fitting over the part 1'. In this instance, a spindle 7' is provided, similar to the spindle, 7, but is secured to an ex- 10 tension, 10' in the lower member 1'. The member 1' has formed near its top an inclined cam member 9', similar to the cam member 9 of Fig. 2. Extending through this cam member is the spindle 7' 15 already mentioned, and an extension, 11', formed on the member 2', this extension being similar to the extension 11 of Fig. 2, and carrying a pin, 12', similar to the pin 12 of Fig. 2. As before pointed out in con- 20 nection with the description of the other figures, the extension, 11', is really a shoulder formed on the extension E carried or formed in the upper member, in this instance, but in the other figures carried or 25 formed in the lower member and there designated as the part 10. A boss 3' is formed on the cup, 1', to which a clamping member is to be pivotally secured, the clamping member to be fastened to the gate. 30 In use the member 1' is filled with oil or any suitable lubricant. In this hinge a slot is provided in the cam member to permit the hinge to be assembled.

It will be seen from the foregoing description that I have provided a very useful, cheap and compact hinge. One that will be well protected from foreign substances, and which will be well lubricated, at all times, insuring a long life for the hinge. The 35 manner in which I have shown the hinge attached to a gate is a good feature also, as not only is the hinge applied quickly to the gate, but by reason of the pivotal arrangement I have, the lower hinge or the other 40 hinge, may be quickly put in place at any point desired along the gate, the trouble of getting the hinges set just right relative to each other being entirely eliminated.

I appreciate the fact that others skilled in 45 the art could make various changes in the details of construction and arrangement of parts herein shown, but this could be done without departing from the spirit and scope of the invention. I therefore do not wish to 55 be limited to the precise construction and arrangements of parts herein shown.

What I claim is:-

1. In a hinge, the combination of an upper stationary member having telescopic 60 walls, a lower member adapted to be partly revolved and having walls telescopically engaging said stationary member, one member being formed with an inclined surface, and means formed integral with the lower mem- 65 ber and slidably engaging the inclined sur-

face of the other member, to suspend the lower member from the upper stationary member, said means being within the telescopic walls of said members.

2. In a hinge, the combination of an upper stationary member having telescopic walls, a lower member adapted to be partly revolved and having walls telescopically engaging said stationary member, one member being formed with an inclined surface, 70 and means formed integral with the other member and slidably engaging the inclined surface of the first named member, to suspend the lower member from the upper stationary member, said means being within 75 the telescopic walls of said members.

3. In a hinge, the combination of an upper stationary member having telescopic walls, a lower member adapted to be partly revolved, and having walls telescopically 80 engaging said stationary member, one member being formed with an inclined surface, guiding means carried by the upper member for guiding the lower member, means formed integral with the one member to slidably engage the inclined surface of the other member, to suspend the lower member from the upper stationary member, said means being within the telescopic walls of said members. 85

4. In a hinge, the combination of one upper stationary member and one lower member adapted to be partly revolved, one member being formed with an inclined surface, means formed integral with the other member and slidably engaging the inclined 90 surface of the first named member to suspend one member to the other, an oil bath for lubricating the inclined surface of the one member and the carrying means of the other member, said oil bath being confined 95 in the lower member.

5. In a hinge the combination of coöperating telescopic members, one upper member being stationary and having two telescopic walls, the lower one being adapted to partly revolve and suspended from the upper member and arranged with walls to telescopically engage the upper member, and mechanism in said members to automatically 100 control the lower partly revolving member. 110

6. In a hinge, the combination of coöperating telescopic members, one upper member being stationary and having two telescopic walls, the lower one being adapted to partly revolve and suspended from the upper member and arranged with walls to telescopically engage the upper member, mechanism in said members to automatically 115 control the lower partly revolving member, the lower partly revolving member adapted to 120 confine a lubricant for the mechanism inclosed in the telescopic members. 125

7. In a hinge constructed to be suspended from a structure and for suspending a load, coöperating members of which the upper 130

member is suspended to a structure, the lower one suspended from the upper one and the load suspended to the same, a centering place for the lower member, and coöperating means in both of said members whereby said lower member is centered.

8. In a gravity hinge, the combination of coöperating telescopic members constructed so one member is suspended in a vertical position in a straight line under the upper member, means to apply the upper member to a structure and means to apply a load to the lower member.

9. In a gravity hinge, the combination of

coöperating telescoping members constructed so one member is suspended in a vertical position in a straight line under the upper member, means to apply the upper member to a structure, and means to apply a load to the lower member, the walls of the upper member inclosing the lower member.

In testimony whereof, I have signed my name to this specification in the presence of two subscribing witnesses.

AUGUST SUNDH.
